CLAIM

The ornamental design for a plant display apparatus, as shown and described.

DESCRIPTION

FIG. 1 is a top, front, and left side perspective view of a first embodiment of a plant display apparatus.

FIG. 2 is a bottom, rear, and right side perspective view of the apparatus of FIG. 1.

FIG. 3 is a front view of the embodiment of the apparatus of FIG. 1.

FIG. 4 is a rear view of the embodiment of the apparatus of FIG. 1.

FIG. 5 is a left side view of the embodiment of the apparatus of FIG. 1.

FIG. 6 is a right side view of the embodiment of the apparatus of FIG. 1.

FIG. 7 is a top view of the embodiment of the apparatus of FIG. 1.

FIG. 8 is a bottom view of the embodiment of the apparatus of FIG. 1.

FIG. 9 is a top, front, and left side perspective view of a second embodiment of a plant display apparatus.

FIG. 10 is a bottom, rear, and right side perspective view of the embodiment of the apparatus of FIG. 9.

FIG. 11 is a front view of the embodiment of the apparatus of FIG. 9.

FIG. 12 is a rear view of the embodiment of the apparatus of FIG. 9.

FIG. 13 is a left side view of the embodiment of the apparatus of FIG. 9.

FIG. 14 is a right side view of the embodiment of the apparatus of FIG. 9.

FIG. 15 is a top view of the embodiment of the apparatus of FIG. 9; and,

FIG. 16 is a bottom view of the embodiment of the apparatus of FIG. 9.

The broken lines depict portions of the article that form no part of the claimed design.
